(57) CLAIM

The ornamental design for the ice cream scoop, as shown and described.

DESCRIPTION

FIG. 1 is a front elevation of an ice cream scoop showing my new design; The rear elevation is a convergence of all views opposite to the front end.

FIG. 2 is a right side elevation thereof; The left side elevation is a mirror image of the right side.

FIG. 3 is a top plan view thereof;

FIG. 4 is a bottom plan view thereof; and,

FIG. 5 is a perspective view thereof.
